CLAIM

The ornamental design for a continuous passive motion
system control unit, as shown and described.

DESCRIPTION

FIG. 1 is a perspective view of a continuous passive
motion system control unit showing our new design;

FIG. 2 is a top plan view thereof;

FIG. 3 is a front elevational view thereof;

FIG. 4 is a side elevational view as seen from the side
opposite of that shown in FIG. 1;

FIG. 5 is a side elevational view as seen from the side
shown in FIG. 1;

FIG. 6 is a rear elevational view thereof; and

FIG. 7 is a bottom plan view thereof.
